Richard Hassel

UNITED STATES PATENT OFFICE.

RICHARD HASSEL, OF BURLINGTON, IOWA.

HAME-TUG.

SPECIFICATION forming part of Letters Patent No. 374,962, dated December 20, 1887.

Application filed April 2, 1887. Serial No. 233,536. (No model.)

To all whom it may concern:

Be it known that I, RICHARD HASSEL, a citizen of the United States, residing at Burlington, in the county of Des Moines and State 5 of Iowa, have invented a new and useful Improvement in Hame-Tugs, of which the following is a specification.

My invention relates to improvements in hame-tugs, in which a body-plate having elevated loops and being further provided with a series of circular holes, each of which, having an upwardly-curved post, operates in conjunction with an eye-piece suitably attached to the end of the trace; and the object of my 15 invention is to furnish a hame-tug which shall keep the trace in a straight line and prevent the eye-piece from rubbing against the leather covering, so that it may be worn with ease. I accomplish this by the mechanism illustrated 20 in the accompanying drawings, in which—

Figure 1 shows a view of my plate. Fig. 2 shows the end of the trace provided with the eye-piece. Fig. 3 represents a longitudinal cross-section of the plate with the trace in 25 place.

Similar letters refer to similar parts throughout the several views.

In my drawings, A represents the plate, having in one end the loop K, by means of which 30 it is connected with the joint G.

B is an elevated loop, preferably square and situated in the other end of the plate A.

M is a trace which passes through the loop B, as illustrated in Fig. 3 of my drawings.

C and C represent elevated loops on the plate A, into which the straps for the harness-pad and belly-band are respectively fastened.

E represent a series of curved posts, one for each circular hole in the plate A. It will 40 be seen that these posts are curved irrespective of the side of the harness where the plate is used.

I represents an eye-piece suitably attached to the end of a trace, M. This eye is fastened 45 over one of the respective posts E in the holes of the plate A. A series of holes and posts

are made use of for the purpose of lengthening and shortening the trace.

H represents a leather covering underneath the plate A, and is attached thereto by the 50 rivets D and F F.

The operation of my invention is as follows: The joint G is fastened in suitable manner to the hame of an ordinary harness. To joint G the plate A is fastened through loop K. Then 55 the plate A is furthermore fastened by means of the loops C and C to the straps of the harness-pad and belly-band, respectively. Thereupon the trace M, provided with the eye-piece I in one end, is in this end passed through the 60 loop B, and the eye-piece I is hooked over one of the series of posts E contained in the holes of the plate A, whereby the trace is fastened to the plate A. I am aware that heretofore 65 hame-tugs have been made with a body-plate operating in conjunction with fastenings attached to this trace. I therefore do not claim such combination, broadly.

What I do claim, and desire to secure by 70 Letters Patent, is—

1. In a hame-tug, a plate, A, having the elevated loops B and C C and provided with a series of holes, each of which has a curved post, E, substantially as and for the purpose herein set forth.

2. In a hame-tug, a plate, A, having the elevated loops B and C C and provided with a series of holes, each of which has a curved post, E, in combination with a trace at its one end provided with an eye-piece, I, substantially as and for the purpose herein set forth.

3. A hame-tug comprising the joint G and the plate A, having loops K B and C C, and a series of holes provided with the post E and the trace M, having the eye-piece I, all substantially as and for the purpose herein set forth.

RICHARD HASSEL.
